UNITED STATES PATENT OFFICE.

JULIAN S. HEXTHER, OF CHICAGO, ILLINOIS, ASSIGNOR TO UNDERWOOD TYPEWRITER COMPANY, OF NEW YORK, N. Y., A CORPORATION OF DELAWARE.

TYPEWRITING MACHINE.

Application filed March 1, 1923. Serial No. 622,010.

To all whom it may concern:

Be it known that I, JULIAN S. HEXTHER, a citizen of the United States, residing in Chicago, in the county of Cook and State of Illinois, have invented certain new and useful Improvements in Typewriting Machines, of which the following is a specification.

This invention relates to typewriting machines, and more particularly to means which may be applied to that class of typewriting machines known as bookkeeping machines, whereby a continuous work-sheet having a succession of similar forms printed thereon may be fed through the machine in such a manner that, at the conclusion of the typing operation which completes the first printed form, it may be gaged for dismemberment from the work-sheet simultaneously with the gaging of the second printed form for typing on its first writing line.

In practice, particularly in banking institutions, the writing of cashiers' checks and drafts is an item that consumes time, especially when these checks are handled as separate forms and when the names, dates and amounts typed or written on perhaps fifty or more of these separate check forms must be further recorded on a proof-sheet. The fact, too, that the writing of these checks or drafts may not be a continuous operation, but may have to be done intermittently during the course of a day's business, further adds to the difficulties encountered in aligning numerous check forms on the single proof-sheet, which must be removed from the machine with the completed check form and reinserted with each succeeding check form.

To overcome these difficulties, a table is fastened in position in front of and above the platen of the typewriter. As the typing operation progresses, the leading edge of the work-sheet bearing the printed check forms is guided over the face of this table while the leading edges of the proof-sheet and the interleaved carbon-sheet are guided by paper-fingers through a space left between the bottom edge of the table and the platen to a position in back of the table and over the regular front paper-table of the machine. At the conclusion of the typing operation which finishes the first check form printed on the work-sheet, the leading edge of the work-sheet is advanced until it touches

a gage on the table. This operation brings the perforated line of detachment which separates the first from the second printed check form under a severing knife, and at the same time advances the first writing line of the second check form to the point of writing in readiness to duplicate the complete operation. It will be noted that the manipulation of the work-sheet bearing the printed check forms does not disturb the proof-sheet, and that, at the conclusion of the operation described above, the proof-sheet will be in correct position to receive the impression of the matter to be typed on the second check form.

Other features and advantages will hereinafter appear.

In the accompanying drawings, Figure 1 is a front elevation of the platen-frame of a typewriter to which my device has been attached.

Figure 2 is a partial sectional view showing my device attached to the platen-frame.

Figure 3 is a detail view of one end of the web-severing knife showing the method of holding the knife in the severing position with a spring member.

Figure 4 is a diagrammatic view of the leading edge of a sample web showing the check form divisions thereof.

As is usual in a typewriting machine, a platen 5 is mounted on a platen-axle 6 which is journaled in end members 7 of a movable carriage 8. Also journaled in the end members 7 is a transverse shaft 9 on which are slidably mounted paper-fingers 10. A supporting bar 11, suitably fastened at its ends to the end members 7, carries a bifurcated table 12. Located on the rear, near the top edges of the two halves of the bifurcated table 12, are gage members 13 having upwardly-projecting stop portions 14 protruding through slots 15, which are cut in the body portion of the table 12 for that purpose. The gage members 13 are adjustably attached to the table 12 by means of thumb nuts and screws 16, and are kept in a vertical position by means of pins 17. A knife 18 having arms 19 projecting from its extreme ends is pivotally fastened near the lower edge of the bifurcated table 12 by means of rivets 20. Fastened to each of the arms 19 of the knife 18 are spring members 21 which have formed thereon finger-pieces

22 for raising the knife 18 from its operative position and catches 23 for holding the knife when it is in operative position.

In operation, a work-sheet 24, having a 5 plurality of forms 25 printed thereon which are divided from one another by weakened lines of detachment 26, is superimposed over another work-sheet 27 and a carbon-sheet is interleaved therebetween. The superimposed work-sheets 24 and 27 are fed into the machine in the usual manner until their leading edges appear above the writing line scale of the typewriter. The leading edge of the work-sheet 27 is then separated from 10 the leading edge of the work-sheet 24 and is guided, together with the interleaved carbon-sheet, underneath the paper-fingers 10 and behind the front paper-table of the machine. At the same time, the leading edge 15 of the work-sheet 24 is guided underneath the lifted knife 18 and over the surface of the bifurcated table 12. As soon as the first writing line of the first form 25 appears under the writing point of the machine, the 20 operator starts typing the matter that is intended to be filled in. At the conclusion of the typing operation which completes the first form 25, the work-sheet 24 is advanced until the leading edge of the work-sheet 25 25 is resting against the upwardly-projecting stop 14 of the gage 13. This operation leaves the weakened line of detachment 26 separating the first and second of the forms 25 directly under the cutting edge of the 30 knife 18, which had previously been restored to its normal position. The same operation has brought the first line of typing of the second of the printed forms 25 to the writing point of the machine. The first form 25 may 35 now be torn from the body of the work-sheet 24, leaving the second form 25, and the work-sheet 27, which has remained intact during the form-severing operation, in position for the operator to duplicate the entire operation.

Variations may be resorted to within the scope of the invention, and portions of the improvements may be used without others.

Having thus described my invention, I 50 claim:

1. In a typewriting machine, the combination with a platen, of a front paper-table above the platen having openings in the upper portion thereof, L-shaped gage-members, 55 each comprising a leg extending downward along the rear of the paper-table to one of said openings, and a forwardly-extending leg projecting through the opening with its sides in engagement with the sides of the opening, and means above the openings for securing the downwardly-extending legs of the gage-members in adjusted positions upon the back of the paper-table.

2. In a typewriting machine, the combination 60 with a platen, of a front paper-table

above the platen having openings in the upper portion thereof, L-shaped gage-members, each comprising a leg extending downward along the rear of the paper-table to one of said openings, and a forwardly-extending leg projecting forward through the opening with its sides in engagement with the sides of the opening, means above the opening for securing the downwardly-extending legs of the gage-members in adjusted positions upon the back of the paper-table, and means engaging the downwardly-extending legs of the gage-members to prevent turning thereof.

3. In a typewriting machine, the combination with a platen, of a front paper-table above the platen, a knife having supporting arms at its ends pivoted on the front paper-table, the knife being swingable away from the front paper-table, substantially in the direction of the pull upon the knife at web-severing, and spring-catches on the knife arranged to lock the knife to the table against yielding in response to said pull and having gripping portions for the digital swinging 90 of the knife away from the face of the front paper-table.

4. In a typewriting machine, the combination with a platen, of a front paper-table above the platen, a knife or gage having supporting arms at its ends pivoted on the front paper-table, the knife or gage being swingable away from the front paper-table, substantially in the direction of the pull upon the knife or gage at web-severing, and towards the front paper-table to a position above the lowermost portion of the paper-table and immediately adjacent the face of the front paper-table, spring-catches on the knife or gage arranged to lock the knife or gage to the table against yielding in response to said pull, and means for mounting the table and the knife or gage as a unit upon the machine.

5. In a typewriting machine, in combination, a bifurcated supporting and guiding table having upturned side edges, substantially square openings in the upper portions of its two halves, and guiding and fastening pin members situated on the vertical axes of said openings, said fastening pin members being provided with thumb nuts, duplicate gaging means slidably mounted on the rear side near the upper edges of the halves of said bifurcated table; and web-severing means pivotally mounted near the lower edge of said bifurcated table.

6. In a typewriting machine, in combination, a bifurcated supporting and guiding table having upturned side edges, substantially square openings in the upper portions of its two halves, and guiding and fastening pin members situated on the vertical axes of said openings, said fastening pin members being provided with thumb nuts, duplicate

- gaging means slidably mounted on the rear side near the upper edges of the halves of said bifurcated table, said gaging means having body portions provided with vertical 5 slots to receive said guiding and fastening pin members, upturned stop portions protruding through said openings in said bifurcated table, and web-severing means pivotally mounted near the lower edge of said bifurcated table.
7. In a typewriting machine, in combination, a bifurcated supporting and guiding table having upturned side edges, substantially square openings in the upper portions 10 of its two halves, and guiding and fastening pin members situated on the vertical axes of said openings, said fastening pin members being provided with thumb nuts, duplicate gaging means slidably mounted on the rear side near the upper edges of the halves of said bifurcated table, said gaging means having body portions provided with vertical slots to receive said guiding and fastening pin members, upturned stop portions protruding through said openings in said bifurcated table, and web-severing means pivotally mounted near the lower edge of said bifurcated table, said web-severing means comprising a knife member having projecting arm members at its extreme ends which are fastened to said upturned side edges of said bifurcated table by means of rivets and spring members fastened to said projecting arm members, said spring members having formed thereon finger-pieces for raising and lowering said knife member and catches for holding said knife member in operative position.
8. In a typewriting machine, the combination of a revoluble platen, means for feeding an inner and an outer work-web around said platen, a front table for supporting said outer web as it is delivered by said platen, said inner work-web advancing underneath said front table, a severing and line-finding gage for gaging a leading form on said outer work-web for severance after the completion of the typing operation, and simultaneously positioning the next succeeding form on said outer work-web to receive a line of typing, and means for severing said outer work-web, said severing means being above the lowermost edge of said front table, the new leading edge of the outer work-web remaining between said front table and said severing means.
9. In a typewriting machine, the combination of a revoluble platen, means for feeding an inner and an outer work-web around said platen, the outer work-web being narrower than the inner work-web, a front table for supporting the outer work-web as it is delivered by said platen, a paper-finger at each side of said table for guiding the inner work-web underneath the lowermost edge 65 of said front table, means for gaging the leading edge of said outer work-web after the completion of the typing operation, and means for severing said outer work-web, said severing means being above the lowermost edge of said front table, the new leading edge of the outer work-web remaining between said front table and said severing means.
10. In a typewriting machine, the combination of a revoluble platen, means for feeding an inner and an outer work-web around said platen, a front table for supporting the outer work-web as it is delivered by said platen, a pair of paper-fingers for guiding 75 the inner work-web underneath the lowermost edge of said front table, and a knife on said table above the lowermost edge thereof for severing said outer work-web, the new leading edge of the outer work-web remaining between said front table and said knife.
11. In a typewriting machine, the combination of a revoluble platen, means for feeding an inner and an outer work-web around said platen, a front table for supporting the 80 outer work-web as it is delivered by said platen, a pair of paper-fingers for guiding the inner work-web underneath the lowermost edge of said front table, a knife on said table above the lowermost edge thereof for 85 severing said outer work-web, the new leading edge of the outer work-web remaining between said front table and said knife, and a pair of side guides for said outer work-web on said front table.
12. In a typewriting machine, the combination of a revoluble platen, means for feeding an outer and an inner work-web around said platen, a front table for supporting the outer work-web as it is delivered by said 90 platen, means for guiding the inner work-web under the lowermost edge of said front table, and a knife pivotally mounted on said table for movement away therefrom to permit the insertion of said outer work-web 95 therebelow in the initial positioning of said outer work-web in the machine, said knife being movable to a position above the lowermost edge of said front table and immediately adjacent the face of said table for 100 severing said outer work-web after the completion of the typing operation, the new leading edge of the outer work-web remaining between said front table and said knife.

JULIAN S. HEXTER.
